UNITED STATES PATENT OFFICE.

WILLIAM PASCHALL, OF BIRMINGHAM, ALABAMA.

FLOOR-SURFACING MACHINE.

Application filed August 13, 1924. Serial No. 731,855.

My said invention relates to a floor surfacing machine and it is an object of the same to provide a machine of this character which shall work rapidly but in which the sand paper covering of the cutting roller shall not gum up and thus interfere with the work.

Another object of the invention is to provide a device of this character with means whereby the cutting drum can be raised for passing over carpets and rugs and which can be raised quickly in case of need to avoid cutting a needlessly deep place in the floor.

Minor objects of the invention are to provide a device in which the main bearings shall be dust-proof, in which the machine can be run close to the wall, which shall be reversible to operate either from the right or left hand side and which may be used to smooth boards before they are made a part of the building.

Referring to the accompanying drawings which are made a part hereof and on which similar reference characters indicate similar parts,

Figure 1 is a side elevation of the machine of my invention,

Figure 2, a section of certain parts in Figure 1,

Figure 3, a rear elevation,

Figure 4, a fragmentary rear elevation of a modified form of the machine,

Figure 5, a plan,

Figure 6, a front elevation of the ring bearings partly in section,

Figure 7, a side elevation of rings and ring bearings shown in Figures 1, 3 and 5,

Figure 8, a rear view of the controlling handle and parts mounted thereon,

Figure 9, a side view of the same,

Figure 10, a fragmentary top plan of parts shown in Figures 8 and 9,

Figure 11, a fragmentary end elevation of parts shown in Figure 9,

Figure 12, a fragmentary side elevation of a modified form,

Figure 13, a section on line 13—13 of Figure 12,

Figure 14, a plan of the rocker plate in the modified form,

Figure 15, a detail of a spring used in said form, and

Figure 16, a detail of a link used therein.

In the drawings reference character 10 indicates the base plate of the machine on

which a motor 11 is supported. Said base plate also supports a pair of outwardly facing ring bearings 12 and 13 held in place by means of brackets 14 (Fig. 6) bolted to the base plate 10, said brackets being either integral with the rings or rigidly secured thereto. The base plate is provided with front wheels 15 and rear wheels 16, the front wheels being carried by an axle 15' secured in any suitable manner to the base. A bracket 17 for the rear wheels is fixed by a bolt 18 to a downward projection of the frame, the bolt forming a pivot on which the bracket 17 may tilt to accommodate inequalities in the floor. The rear wheels 16 are preferably in the form of casters each pivotally connected at 19 to the bracket 17 for movement about a vertical axis. The form shown is that preferred for use in surfacing floors. In Figure 4 I have shown a bracket 20 longer than the bracket 17, said bracket being also pivoted at 18 and carrying at each end a wheel 16 pivoted to the bracket for movement about a vertical axis. By using this wider bracket the wheels may straddle one or more boards loosely supported and thus I am enabled to finish boards not yet attached to the floor or other surface.

Rings 21 and 22 are supported on the respective ring bearings 12 and 13 for pivotal movement about the common central axis of said rings, or taking up wear in these rings I have provided screws 21² extending across a split part of each ring said screws being adapted to clamp the ring bearings more or less tightly to the supporting rings and the rings 21 and 22 being preferably split close to the forwardly extending arms thereon. The rings 21 and 22 have rearward projections to which is attached a cross-bar 23, which has a bracket 24 bolted thereto. This bracket is forked at its rear end to receive a rod 25 held in place between the forks by a bolt 26.

At their forward side the rings 21 and 22 also have projections with curved bars 27 above them and an arm 28 secured in any suitable manner to one or the other of said projections. In the illustrated embodiment of the invention the arm 28 has an integral lateral extension reaching across the machine behind the drum and the dustpan 29 comprises one or more pieces of sheet metal riveted to the lateral extension of the arm, the

dustpan extending both up and down from said extension. Cap screws 29 engage in threaded holes in the extension and are inclined rearwardly so that they may catch in hooks 21', 22' on the forward projections of respective rings 21 and 22, said hooks serving to hold the drum and its supporting and driving means. The dustpan has flanges at its ends extending forward and close to the drum 30 or down past its ends, and is supported in part by an integral bar extending laterally from arm 28 over the drum which is rotatably supported in anti-friction bearings carried by the arm 28 said bearings 15 in this instance comprising a ball bearing 31 on a housing 32 fast to the outer face of the arm 28 and a roller bearing 33 approximately midway of the drum in a hollow spindle 34 formed integral with the arm 28. 20 It will be obvious to those skilled in the art that the kind and arrangement of bearings may be varied without departing from the invention.

The roller 30 is the cutting part of the 25 machine and has an outer layer 35 of felt or soft rubber or the like with any convenient means for attachment of an outer layer of sandpaper. The inner shell 36 of the drum is spaced from and secured to the outer 30 tapered end of the spindle 37 by a collar 38 having a tapering bearing corresponding to the surface of the spindle and held in place by any suitable means here shown as a nut.

35 Adjacent the forward end of the stationary spindle 34 a hollow plug 39 is screwed into the same to hold the casing of the roller bearing 33 in place said plug having a flange approximately closing the space between the 40 spindle and shaft 37. Within the cavity of the plug the shaft is provided with a centrifugal oil ring 40 to prevent escape of oil between the two bearings, said ring being part of a nut which bears against the inner 45 sleeve of the roller bearing. A worm 41 is fastened to the shaft 37, said worm meshing with a worm gear 42 fixed to an eccentric sleeve 43 journaled on a fixed pin 44 passing through the arm 28 (Fig. 5). A housing 45 extends over the worm 41 and about its 50 ends, said worm-housing supporting and being spaced from the ends of the worm by ball bearings 46 at each end of the worm and pins 45' (Fig. 11) are brazed to the exterior of said worm housing adjacent one 55 end thereof, these pins extending from levers 47, or if desired from a single lever straddling the worm housing. A link 48 connects the eccentrically mounted gear 42 to the lever or levers 47. All the parts in the chamber formed by the housing 32 and the hollow spindle 34 run in oil and the chamber is 60 effectively protected from access of dust.

65 On top of the motor a block 49 is secured in any suitable manner and a frame member

50 extends rearwardly and upward from said block. This frame member constitutes means through which the device is steered or guided and in effect is the main handle of the machine. At the rear end of the machine the 70 handle is supported by braces 51 rising from and secured to an upward projection on the base 10. Outwardly spaced from the points of attachment of the brace members 51 to the base openings are formed in said upward projection to receive a pair of spring bars 52 having fulcrums at 52' and being held in place by set-screws 53. These springs are secured at their forward ends by means of links 54 to the arcuate parts 27 on the 80 rings 21 and 22, said parts having spaced holes in a series extending lengthwise of the arms for adjustment of the spring tension. The springs serve to counterbalance the weight of the frame 30 and other parts carried at the forward end of the arms and normally maintain the drum in elevated position out of contact with the floor.

The action of the drum on the floor is 90 controlled by means of the rod 25 which is in two parts connected by a turn-buckle 55 for purposes of adjustment. At the upper end of the upper rod section there is a rack 56 meshing with a pinion 57 loosely supported on a shaft passing through handles 58 on which shaft said handles are rigidly held between the sides of a casting 59 and nuts at the outer ends of the shaft 58. The casting 59 is secured to the upper end of the 100 frame member 50 and provides a track for the rack 56, a support for the pinion and a rack segment mounted on a rearwardly projecting arm 62 integral with the pinion 57 said arm carrying a thumb-piece 63 by means of which the operator may strike the handle 64 of the trigger with the side of his hand and simultaneously press down on the thumb-piece with his thumb for quickly releasing the rack and connected parts whereupon the spring bars 52 will instantly swing 110 the loose rings in a direction to throw the drum out of working position away from the floor. The rack segment preferably has a series of teeth at the upper end and a single tooth at the lower end.

115 Another means for controlling the drum is also illustrated in the drawings, the operator having a choice of using either one or the other means. The last-named means consists of a quick-acting nut 67 having internal threads of high pitch meshing with similar threads at the upper end of the rack bar 56. This nut is provided with a handle 68 for convenience in operation. When the trigger control is to be used the quick-acting nut is placed at its highest point so as not to interfere with the control of the drum. The trigger lever is adjusted by means of a turn buckle 55 so that the trigger or detent 120 rides on the lower part of the segment where 125 130

there are no notches to interfere with its movement. The adjustment of the nut 67 against the collar 66 raises or lowers the drum or holds it against the floor being surfaced with the degree of pressure desired. Either one of the controlling means may be omitted if desired or other controlling means may be used within the scope of my invention.

10 A fan casing 69 is secured to the ring 22 slightly above the latter ring; and a plate 70 projects at the end of the fan casing said plate providing a support for the fan by means of which it may be inserted in the 15 casing or removed therefrom. The fan is driven by a belt 71 passing over a pulley 72 on the fan shaft 72 and a pulley 73 on the main shaft. The fan casing is preferably made of cast aluminum and is formed in one 20 with a depending bracket 69' fastened by means of screws to the stationary ring 13, but which may equally well be attached to ring 12. The fan shaft projects at its end remote from the fan casing through a bearing 79 on ring bearing 21 to a sufficient distance to permit the pulley 72 when removed to be positioned on the opposite end of the fan shaft. The bearing 79 is fixed to the 25 ring 13 in any convenient manner as by means of screws. A conduit 74 leads from the dust-pan to the fan casing whereby the fan serves to withdraw dust from the dust-pan and a conduit 75 extends from the other side of the fan casing said latter conduit 30 leading to any suitable receptacle.

The main shaft in addition to the pulley 73 carries a sprocket 76 over which passes a sprocket chain 77 which drives the sprocket gear 78 on the shaft 37 of the surfacing drum.

40 In the operation of my device the position of the drum relative to the floor is first determined by adjustment of the turnbuckle 55 and the rack bar 56, the first adjustment 45 being relatively permanent and the second being subject to change whenever the drum is raised from the floor. The motor being now started the drum will be revolved and the fan will be driven. As the drum rotates 50 the gear 41 turns with it and turns the eccentrically mounted gear 42 about the pin 43 thereby moving the lever 47 through the link 48 about its pivot 48'. The lever being connected to the worm housing by the pin (or pins) 45' moves the worm housing with the shaft 37 and parts carried thereby in the axial direction of the shaft so that the drum 55 reciprocates to a slight extent as it rotates in its operation on the floor. This 60 prevents gumming of the sandpaper on the drum and causes it to wear longer, at the same time making a smoother surface with less work. Should slight obstructions such as knots in the floor be encountered the 65 drum can rise slightly due to the resiliency

of spring 65 after which it will return to ordinary working position. If it is necessary to stop the machine as at the end of a room the tripping arrangement on the casting 59 provides quick release means for the rod 25 whereby the drum can be lifted off the floor and accidental return of the drum can be prevented by turning the nut 67 down against the abutment 66 if desired.

70 In the case of machines which are not reversible, a great deal of hand work is necessary in finishing floors close to one wall of a room for the reason that the drum cannot run close to the wall at the left-hand side of the machine as shown in Figure 5. The device of my invention is so constructed that it may be quickly reversed so as to run close to the wall at the side here indicated as being at the left of the machine. For this purpose the cap screws 29' resting in the 75 hooks on the upward projections of the rings are loosened. The drum frame may then be lifted up and turned end for end which places the gear housing on the right-hand side of the machine. The drum being reversed the cap screws are inserted in the hooks and tightened to hold the drum and housing in place. The fan pulley and the sprocket gear 76 are now removed from the 80 motor shaft and placed on the right-hand end thereof so that the driving sprocket lines up with the driven sprocket as before and the driving fan pulley lines up with the driven fan pulley which has also been 85 removed from the position illustrated and placed on the right-hand end of the fan shaft. Since the outlet from the dust-pan is symmetrical about the arm 28 the reversal does not affect it. The remaining parts of the machine are left as before. recesses at the ends of the base 10. These brackets are bolted or otherwise removably secured to opposite ends of the rocker plate.

The rocker plate has an elevated flat bearing surface at 87 on which a semi-elliptical spring 88 rests midway between its ends. At the ends of the spring cap screws 89 are threaded through the base 10 for adjusting the tension of the spring, these cap screws being held against accidental rotation by lock nuts 90.

As in the modification heretofore described the rings have forwardly extending projections which in this instance are cored out as indicated at 91 to receive links 92 which rest on cross-bars 93 (Fig. 15) at the forward ends of springs 94, the cross-bars being formed by punching spaced holes through each of the springs 94. The springs, as in the preceding modification, are held at their rear ends in apertures provided in upwardly extending blocks on the base 10 and rest adjacent such blocks on fulcrums 95. For adjusting the tension of a spring the screw 96 which holds it in place is backed off and the spring is moved in or out of the aperture in the block.

Figure 14 shows a plan of the block with holes 97 to receive the cap screw 89 and with reinforcing ribs 98 on its under side. The bearing 99 for the rod 82 is also indicated in this figure.

Knots and the like are frequently encountered in operating on floors and if they strike the drum near one end a twisting strain is occasioned in the machine unless some provision is made for avoiding the same. In the form of the invention last described the ring frame is rigidly connected to the rocker plate 84 and as will be remembered the ring frame supports the drum. Inasmuch as the rocker is allowed to move it will be obvious that the drum may tilt to a limited extent against the force of the spring 88 to allow the drum to rise slightly at one end or the other after which it will resume its horizontal position. The cored out portions at 91 allow the links 92 to move with sufficient freedom while at the same time they are securely connected to the springs 94 in that the lower ends of the links straddle the cross-bars 93 of the springs.

Having thus fully described my said invention, what I claim as new and desire to secure by Letters Patent, is:

1. A floor surfacing machine comprising a base, a pair of coaxial upright ring bearings supported on the base, rings pivotally mounted on said ring bearings, arms extending forward from the rings, a surfacing drum on said arms, arms projecting rearwardly from said rings, a main handle also projecting rearwardly, and connections between said handle and said rearwardly

projecting arms for varying the relation of the drum to the floor, substantially as set forth.

2. A floor surfacing machine comprising a base, a pair of coaxial upright ring bearings supported on the base, rings pivotally mounted on said ring bearings, arms extending forward from the rings, a surfacing drum on said arms, and means connected to said arms for counterbalancing the weight of the drum, substantially as set forth.

3. A floor surfacing machine comprising a base, a pair of coaxial upright ring bearings supported on the base, rings pivotally mounted on said ring bearings, arms extending forward from the rings, a surfacing drum on said arms, means connected to said arms for counterbalancing the weight of the drum, and a motor on the base between said ring bearings for driving the drum, substantially as set forth.

4. A floor surfacing machine comprising a base, a pair of coaxial upright ring bearings supported on the base, rings pivotally mounted on said ring bearings, arms extending forward from the rings, a surfacing drum on said arms, and means connected to said arms for counterbalancing the weight of the drum said means including leaf springs attached to the base behind the ring bearings and connected at the forward ends to said arms, substantially as set forth.

5. A floor surfacing machine comprising a base, a pair of coaxial upright ring bearings supported on the base, rings pivotally mounted on said ring bearings, arms extending forward from the rings, a surfacing drum on said arms, and means connected to said arms for counterbalancing the weight of the drum said means including springs between the drum supporting means and the fixed frame of the machine, substantially as set forth.

6. A floor surfacing machine comprising a base, a pair of coaxial upright ring bearings supported on the base, rings pivotally mounted on said ring bearings, arms extending forward from the rings, a surfacing drum on said arms, a motor mounted coaxially with said rings, driving gearing connecting the motor to the drum, a ring secured to one of said first-named rings in radially spaced relation thereto, a fan removably supported in the casing, driving connections from said motor to said fan, a dust-pan at the rear side of the surface drum, and a conduit from the dust-pan to the fan, substantially as set forth.

7. A floor surfacing machine comprising a base, a pair of coaxial upright ring bearings supported on the base, rings pivotally mounted on said ring bearings, arms extending forward from the rings, a surfacing drum on said arms, a dust-pan movable with

- said drum, a fan, means for driving the same when the machine moves, and connections from the dust-pan to the fan, substantially as set forth.
- 5 8. A floor surfacing machine comprising a base, a pair of coaxial upright ring bearings supported on the base, rings pivotally mounted on said ring bearings, arms extending forward from the rings, a surfacing drum on said arms, a dust-pan movable with said drum, a fan, connections from the dust-pan to the fan, a handle rigidly secured to the base, and connections between said handle and said rings whereby the drum may 15 be forced toward the floor, substantially as set forth.
9. A floor surfacing machine comprising a base, a pair of coaxial upright ring bearings supported on the base, rings pivotally mounted on said ring bearings, arms extending forward from the rings, a surfacing drum on said arms, a dust-pan movable with said drum, a fan, connections from the dust-pan to the fan, a handle rigidly secured to the base, connections between said handle and said rings for forcing the drum toward the floor, and means for counterbalancing the weight of the drum, substantially as set forth.
- 20 10. A floor surfacing machine comprising a base, a pivot fixed in relation thereto, a drum mounted to move about said pivot, driving means for the drum, counterbalancing means normally holding the drum out 25 of contact with the floor, and means for forcing the drum toward the floor including a part fixed to the frame of the machine, a rod connecting said part to the pivotal support of the surfacing drum, and a spring 30 acting directly on the rod for moving said rod in a direction to force the drum toward working position, substantially as set forth.
11. A floor surfacing machine comprising a base, a pivot fixed in relation thereto, a drum mounted to move about said pivot, driving means for the drum, counterbalancing means normally holding the drum out of contact with the floor, means for forcing the drum toward the floor including a part fixed 35 to the frame of the machine, a rod connecting said part to the pivotal support of the surfacing drum, and means for moving said rod in a direction to force the drum toward working position said means including rack 40 teeth on the rod, a pinion having teeth engaging the rack teeth, a bolt movable with the pinion, and a rack bar for engagement by said pawl, substantially as set forth.
12. A floor surfacing machine comprising a base, a pivot fixed in relation thereto, a drum mounted to move about said pivot, driving means for the drum, counterbalancing means normally holding the drum out of contact with the floor, means for forcing the drum toward the floor including a part 45
- fixed to the frame of the machine, a rod connecting said part to the pivotal support of the surfacing drum, and means for moving said rod in a direction to force the drum toward working position said means including a rack and pinion for moving the rod in one direction and a spring surrounding the rod braced to move it in the reverse direction, substantially as set forth. 70
13. A floor surfacing machine comprising a base, a pivot fixed in relation thereto, a drum mounted to move about said pivot, driving means for the drum, counterbalancing means normally holding the drum out of contact with the floor, and means for resiliently forcing the drum toward the floor including a spring acting directly on the rod, a two-part rod connected at one end to a fixed frame member and at the other end to the movable supporting means for the drum, 80 and a turnbuckle between the two parts of the rod, substantially as set forth. 85
14. A floor surfacing machine comprising a surfacing drum adapted to have sandpaper secured thereabout, a shaft extending axially of the drum, a supporting bracket having a hollow spindle surrounding said shaft, gearing within said spindle for reciprocating the drum as it rotates, and a closed oil chamber surrounding said gear- 90 ing and the bearings for said shaft, substantially as set forth. 95
15. A floor surfacing machine comprising a surfacing drum adapted to have sandpaper secured thereabout, a shaft extending axially of the drum, a supporting bracket having a hollow spindle surrounding said shaft, a worm on the shaft, anti-friction bearings spacing the housing from the ends of the worm, means connected to the shaft 100 for reciprocating the worm as it rotates, anti-friction bearings supporting the shaft, and a closed oil chamber including all of said anti-friction bearings, substantially as set forth. 105
16. A floor surfacing machine comprising a surfacing drum adapted to have sandpaper secured thereabout, a shaft extending axially of the drum, a supporting bracket having a hollow spindle surrounding said 110 shaft, a worm on the shaft, anti-friction bearings spacing the housing from the ends of the worm, means connected to the shaft for reciprocating the worm as it rotates, anti-friction bearings supporting the shaft, 115 a closed oil chamber including all of said anti-friction bearings, and means for excluding dust from said chamber including a centrifugal oil ring on the shaft adjacent the end of the hollow spindle, substantially as set forth. 120
17. A floor surfacing machine comprising a base, a motor on the base, a drum driven by the motor adapted to act on a floor, a pair of front wheels on the base, inter- 125
- 130

changeable pivoted brackets for the rear wheels constructed and arranged for pivotal mounting on a horizontal fore-and-aft axis said brackets being respectively wide and narrow, and caster wheels at the ends of said brackets, substantially as set forth.

18. A floor surfacing machine comprising a base, a drum, a frame therefor pivoted transversely of the machine, a handle on 10 the base, connections from the handle to the frame for moving the drum into and out of contact with the floor, means for simultaneously rotating the drum and reciprocating it in the direction of its length, 15 a dust-pan behind the drum, and a fan for carrying off the dust, substantially as set forth.

19. A floor surfacing machine comprising a base, a drum, a frame therefor pivoted 20 transversely of the machine, means operative on the frame for quickly moving the drum into and out of contact with the floor, fine adjusting means for varying its action on the floor, means for simultaneously rotating the drum and reciprocating it in the direction of its length, a dust-pan behind the drum fixed to said frame, and a fan connected to the dust-pan for carrying off the dust, substantially as set forth.

20. A floor surfacing machine comprising a base, a drum, means for rotating the drum, means operated by the rotation of the drum for reciprocating said drum axially of itself said means including an axial shaft for 35 the drum, a worm on the shaft, an eccentric worm-gear meshing with the worm, a housing for the worm movable endwise with the shaft and a lever having connections to the worm-gear and the worm-housing, substantially as set forth.

21. A floor surfacing machine comprising a frame, a rotatable roller on the frame, a dust-pan concentric with the roller and arranged for pivotal movement therewith 45 about an axis extending lengthwise of the machine, substantially as set forth.

22. A floor surfacing machine comprising a base, a frame supported in the base for movement about a horizontal pivot, a drum 50 at the forward end of the support, and counter-balancing springs on the base at opposite sides of the support said springs being pivotally connected to said support at one end and adjustably connected to the base at the other end for varying their tension, substantially as set forth.

23. A floor surfacing machine comprising a wheeled base, a horizontal pivot extending lengthwise thereof, a rocker plate on 55 the pivot, supporting means on the rocker plate including a horizontal pivot at right angles to the first-named pivot, a drum on the frame rotatable about an axis parallel to the last-named pivot, and means for holding the drum yieldably in engagement with

the floor against movement about either of said pivots, substantially as set forth.

24. A floor surfacing machine comprising a truck, a rocking support pivoted thereon to move about an axis extending fore and 70 aft of the machine, springs to hold said frame against movement, a frame on the support pivoted on a transverse axis, and a roller rotatably supported on the frame, substantially as set forth.

25. In a floor surfacing machine, a wheeled base, a pivoted support on the base, a detachable arm reversibly attached to the front of the support, a motor on the base, a drum rotatably mounted at the forward 80 end of the arm, and driving connections between the motor and the drum projecting at one side of the machine the motor shaft having duplicate arrangements at opposite sides of the machine for attachment of said 85 driving connections according to the position of the said detachable arm, said drum extending across the entire front of all parts of the machine except said driving connections in either position of the detachable 90 arm, substantially as set forth.

26. A floor surfacing machine comprising a base, a drum, a frame therefor pivoted transversely of the machine, a handle on 95 the base, connections from the handle to the frame for moving the drum into and out of contact with the floor, means for adjusting said connections to vary the action of the drum on the floor, means for simultaneously rotating the drum and reciprocating 100 it in the direction of its length, a dust-pan behind the drum, and a fan for carrying off the dust, substantially as set forth.

27. A floor surfacing machine comprising a base, a pair of coaxial upright ring bearings supported on the base, rings pivotally mounted on said ring bearings, arms extending forward from the rings, a surfacing drum on said arms, a motor mounted coaxially with said rings, and driving gear 110 connecting the motor to the drum, substantially as set forth.

28. A floor surfacing machine comprising a base, a pair of coaxial upright ring bearings supported on the base, rings pivotally 115 mounted on said bearings, arms extending forward from the rings, a surfacing drum on said arms, a motor for driving said drum, and means for collecting dust raised by the drum, substantially as set forth.

29. A floor surfacing machine comprising a base, a pair of coaxial upright ring bearings supported on the base, rings pivotally mounted on said bearings, arms extending forward from the rings, a surfacing drum 125 on said arms, a motor for driving said drum, means for collecting dust raised by the drum including a fan, and driving connections from the motor to the fan, substantially as set forth.

30. A floor surfacing machine comprising a base, a pair of coaxial upright ring bearings supported on the base, rings pivotally mounted on said ring bearings, arms extending forward from the rings, a surfacing drum on said arms, a motor mounted coaxially with said rings, driving gearing connecting the motor to the drum, a ring secured to one of said first-named rings in spaced relation thereto, a fan removably supported in the casing, and driving connections from said motor to said fan, substantially as set forth.
31. In a floor surfacing machine, a wheeled base, a support on the base, a motor on the base, a drum rotatably mounted at the forward end of the support, means on the base for carrying off dust and the like from the drum, and means for driving the fan and the drum from said motor including a motor shaft and a fan shaft projecting at opposite sides from the machine for connection to the drum shaft when the arm is
- reversed, said drum extending across in front of whichever motor shaft projection 25 is not in use, substantially as set forth.
32. In a floor surfacing machine, a movable base, a support on the base, a drum at the front end of the machine, driving means for the drum including elements projecting 30 laterally beyond either one of the two sides of said base, and means for supporting said drum in either of two opposite positions with said elements projecting either to the right or to the left of the machine, said 35 supporting means leaving one end of the drum free so that said free end can extend in front of all parts of the machine except the driving elements, substantially as set forth.
- 40
- In witness whereof, I have hereunto set my hand at Birmingham, Alabama this 12th day of July, A. D. nineteen hundred and twenty-four.

WILLIAM PASCHALL.
